UNITED STATES PATENT OFFICE.

CHARLES W. LINSCOTT, OF McGRAW, NEW YORK.

REDUCING CORSET.

Application filed March 4, 1922. Serial No. 541,163.

To all whom it may concern:

Be it known that I, CHARLES W. LINSCOTT, a citizen of the United States, residing at McGraw, in the county of Cortland and State 5 of New York, have invented certain new and useful Improvements in Reducing Corsets, of which the following is a specification, reference being had to the accompanying drawings.

- 10 Corsets heretofore used become stretched in time and out of shape, and thereby permitting the body of the wearer to appear out of shape. In other words if the wearer is inclined to become stout, especially around 15 the hips, the fat bulging to an unsightly degree, corsets heretofore manufactured will very soon get out of shape and will not hold the fat in place, and make it appear uniform and shapely.
- 20 Therefore, it is the purpose of the present invention to provide body reducing tabs connected to the opposite sides of the corset, for drawing the same tight, acting materially to reduce the waist, and especially 25 the hips of the wearer, and thereby make the body of the wearer appear shapely, slender and graceful.

Another purpose is the provision of efficient doubled tapes or lacings, which are 30 attached to the opposite tabs and to the plates thereof, so that sufficient power can be applied to the lacings for drawing the tabs together tightly and closely to the body of the wearer, for clasping the plates there- 35 by preventing the corset from unduly stretching and losing its shape, and at the same time permitting the body of the wearer to expand.

Still another purpose is the provision of 40 an arrangement of using lacings, which pass through eyelets, due to the metal tips on the lacings, to insure drawing the corsets tightly and securely in place on the body of the wearer, in a manner to comply with 45 the requirements of the wearer.

A further purpose is the provision of male and female fasteners carried upon the adjacent overlapping ends of the tabs (which are fastened to the opposite side of the corset), so that together with the tabs, the 50 metal plates, which are fastened to the tabs, the tabs may be drawn securely in connected positions by means of lacings, which pass through openings or apertures of the tabs, and then fastened together by means of a 55 clasp. In fact the tabs are stitched to the

opposite side of the corset immediately over the hips, extending from a point adjacent the waist line to and terminating a substantial distance below the hips, so as 60 to draw the hips in, and hold them tightly and securely in reduced positions.

Still a further purpose is the provision of a pair of tabs, with interconnecting or cooperative male and female fasteners, the 65 male fastener being carried by a plate of an overlapping tab, the female fasteners being part of a plate, secured to the underlapping end of the other tab for cooperating with the male fastener of the first tab. The 70 plates carrying the male and female fasteners are mounted in pockets formed in the tabs. Opposite portions of the fabric material of one of the tabs are cut away and stitched to expose the female fasteners, 75 whereby the male fasteners may enter any one of the female fasteners.

It is to be understood that the particulars herein given are in no way limitative and that while still keeping within the scope of 80 the invention, any desired modifications of detail and desired proportions may be made in the apparatus according to circumstances.

The invention comprises further features and combination of parts, as will be herein- 85 after set forth, shown in the drawings and claimed.

In the drawings:—

Figure 1 is a view of a pair of corsets, showing the application of the improved 90 reducing tabs for all kinds of corsets:

Figure 2 is an enlarged detail view of the overlapping ends of the tabs carried by the corsets, showing said ends adjustably and operatively connected;

Figure 3 is a sectional view on line 3—3 of Figure 2;

Figure 4 is an enlarged detail view of one of the tabs, which carry the metal plate having the female fasteners; and

Figure 5 is an enlarged detail view of a pair of interconnecting hooks which are used below the tabs.

Referring to the drawings, 1 designates a pair of corsets of general construction, which 105 may be any suitable shape and size and constructed of any suitable material. Stitched to the opposite sides of the corset at the hips as at 2 and extending from the waist line to a location a substantial distance below the hips are tabs or extensions 110 3, which overlap and operatively connect

at a point over the base of the stomach, in fact a little below the waist line. In other words the tabs where they connect are reduced in size or tapered. The marginal edges of the tabs 3 are stitched as at 4, and both tabs are made of a double thickness of material. The smaller ends of the tabs are designed to overlap, and are provided with pockets 7 in which metal plates 8 and 8^a are arranged. The stitching 4 of the tabs extend about three of the edges of the plates 8 and 8^a. Additional stitching 9 and 9^a extend vertically across the tabs adjacent the remote edges of the plates 8 and 8^a, thereby holding the plates in position in the pockets. As previously stated the tabs are constructed of double thicknesses of material, and the opposite thicknesses of material of one of the tabs are provided with cut away portions or openings 5. These openings 5 are large enough to expose the openings 10 in the reinforcing plate 8. There are three openings 10, though it is obvious that any number of such openings may be used. Each opening 10 comprises larger and smaller ends, and the intermediate passage 11. The margins of the openings 5 are stitched as at 5^a to prevent the fabric from fraying out or unraveling, thereby presenting a neat appearance.

The overlapping end of one of the tabs has a post or male fastener 12, which extends inwardly, and is adapted to enter any one of the openings 10 of the plate 8, to hold the adjacent ends of the tabs connected and overlapped. In fact the post or male fastener 12 is carried by the plate 8^a, in order to firmly support the same rigidly, and to withstand the strain thereon. The overlapping end of the tab, which carries the post or male fastener 12, is provided with a single finger loop 13, which may be engaged by the finger of the wearer for imparting a pulling action on the tab to draw it in a direction toward the other tab, and enable the male fastener to enter one of the female fasteners or openings 10.

In order to additionally secure the plate 8^a in the pocket of one of the tabs, riveted 50 eyelets 14 and 15 are provided. These eyelets are arranged through the fabric material of the tab and through the plate 8^a.

The underlapping tab is provided with eyelets 16 and 17 similar to the eyelets 14 and 15, and these are also arranged through the fabric material of the tab and through the plate 8.

Double lacings 18 are secured in any suitable manner to the underlapping tab, for instance by means of the eyelets 16, and these lacings or strands 18 pass through the eyelet 15. Double lacings 20 are attached to the overlapping tab, for example by means of the eyelets 14, and are then passed 65 through the eyelet 17. The lacings 18 and

20 are brought together in front, and are used for the purpose of drawing the two tabs toward each other in overlapping positions, until the wearer feels that the corsets are tight enough, then the post 12 is inserted 70 through one of the openings 10, and then the pulling action upon the lacings or strands is released. The tabs will then stay connected and in order to keep the strands or lacings from hanging down, they may 75 be brought together in front, and connected by a suitable fastener or clasp 20^a. However it is obvious that if desired the strands or lacings 18 and 20, after they have performed their purpose, may be allowed to 80 hang down or supported out of the way in any other suitable manner, as found convenient by the wearer. In fact the lacings or strands 18 are connected to the under surface of the underlapping tab, whereas the 85 lacings or strands 20 are likewise connected to the tab carrying the plate 8^a. As previously stated these strands or lacings pass through the eyelets 15 and 17, so as to be arranged on the exterior of the tabs. 90

When it is desired to disconnect the tabs the finger of the wearer may engage the loop 13, for the purpose of pulling one of the tabs, sufficiently to locate the post or male fastener 12 adjacent the larger end of the 95 opening 10 with which it engages then the post or male fastener 12 may be withdrawn from the opening, in which case the tabs are then disconnected. The corsets may then be removed, after separating their front 100 edges, by disconnecting the clasps and the hooks. The hooks 2^a and 2^b are carried by the lower portions of the front edges of the corsets, and are designed to interengage, to hold the lower parts of the corsets in position. These hooks and eyes 2^a and 2^b are arranged from a point just below the lower edges of the extremities of the tabs, to a point adjacent the lower edge of the front 105 of the corset. The usual corset clasps 2^c connect the upper portions of the front edges of the corsets, that is from a point adjacent the upper edges of the extremities of the tabs, to a point adjacent the upper edge of the corsets. 110

The extremities of the lacings or strands 18 and 20 are connected in slots of metal plates or tips 19, which are used for inserting the ends of the lacings or strands through the eyelets 15 and 17. It is obvious that should the lacings 18 and 20 become detached from the eyelets 14 and 16, other lacings may be attached, by simply passing the lacings through the eyelets 15 and 16, and construct knots on opposite 120 sides, thereby preventing the strands from detaching or pulling away.

The eyelets 14 and 16 serve the double purpose of attaching the strands or lacings to the tabs, and for holding the plates 8 and 130

8^a firmly in position and connected to the fabric of the tabs. The eyelets 15 and 17 also perform double fold purposes of assisting in holding the plates 8 and 8^a in place, 5 and serving to receive the strands or lacings.

It will be noted that the passage connecting the larger and smaller ends of each opening 10 is provided for the purpose of rendering it difficult for the post, stud or 10 male fastener 12 to pass from one end to the other of the opening 10. By providing a restricted passage of this kind, the adjacent overlapping ends of the tabs are prevented from accidentally disconnecting.

15 Secured to the front portions of the opposite sides of the corsets as at 22 by means of stitching are elastic uplifts 23, which extend toward the opposite sides of the corsets, and the ends of these elastic uplifts 20 have reinforcing stays 24, and provided with eyelets or openings 25. The elastic uplifts 23 are stitched to the corsets adjacent stays 26, so as to insure reinforcement, and to insure a uniform tightening of the corsets 25 when worn. Secured by stitching as at 27 to the corsets adjacent the side portions thereof are extensions or flaps 28, which have reinforcing stays 29. These extensions or flaps 28 have eyelets or openings 30, 30 which receive the lacings 31, which are also engaged through the eyelets or openings 25. The lacings are tied in bow knots as at 32, to insure holding the parts connected. The elastic uplifts 23 insure a constant tension 35 upon the body of the wearer, in order to insure holding the fat around the hips in place.

To attach the lacings 18 and 20 to the tabs, it is accomplished before the eyelets 40 are finally clinched. In other words before clinching the eyelets 14 and 16 the lacings are given a turn around the shanks of the eyelets, then their shanks are clinched.

While it is stated and illustrated that 45 the lacings 18 and 20 are attached to the tabs by means of the eyelets 14 and 16, it is obvious that they may be secured to the tabs by any other suitable means such as stitches. The stitches for attaching the lacings may 50 be used because of presenting a neater appearance. However, the eyelets are used because they serve the double purpose of attaching the lacings in the first instance and enabling quick repairs to be given in the second instance. For example should the lacings 55 break or become detached, the wearer may readily reattach the lacings by knotting them in the eyelets. If necessary the lacings may be restitched to the tabs, in case they break. 60 Also the eyelets serve to hold the plates in place as well as holding the covering of fabric to the plates.

The invention having been set forth, what is claimed is:—

65 1. As an article of manufacture, a corset

comprising a body, a pair of reducing tabs fastened to the opposite sides of the corset extending from the waist downwardly beyond the lower portion of the hips, said tabs having overlapping ends at the front, 70 said ends provided with male and female fasteners adjustably connecting said overlapping ends, and drawing or tightening lacings interconnecting the overlapping ends, whereby the tabs may be loosened or 75 tightened, to enable the fasteners to connect and disconnect.

2. As an article of manufacture, a corset comprising a body, a pair of reducing tabs fastened to the opposite sides of the corset 80 extending from the waist downwardly beyond the lower portion of the hips, said tabs having overlapping ends at the front, said ends provided with male and female fasteners adjustably connecting said overlapping ends, and drawing or tightening lacings interconnecting the overlapping ends, whereby the tabs may be loosened or 85 tightened, to enable the fasteners to connect and disconnect, and means carried by 90 the overlapping end to be engaged by the finger of the wearer, to disengage the connected ends of the tabs.

3. As an article of manufacture, a corset comprising a body to securely embrace the 95 waist and hips, a pair of tabs connected to the opposite sides of the body and extending down over the hips a substantial distance, said tabs terminating in overlapping ends, plates extending the height of the ends 100 and secured therein, said plates being of widths extending from the edges of the ends a substantial distance toward the hips, means comprising eyelets for fastening said plates between the opposite pieces of material of said ends, one of said plates having a fastener member, the other plate having a plurality of openings, either one of which being adapted to receive said fastener member, for holding the tabs permanently 110 fastened after once being connected.

4. As an article of manufacture, a corset comprising a body to securely embrace the waist and hips, a pair of tabs connected to the opposite sides of the body and extending down over the hips a substantial distance, said tabs terminating in overlapping ends, plates extending the height of the ends 115 and secured therein, said plates being of widths extending from the edges of the ends 120 a substantial distance toward the hips, means comprising eyelets for fastening said plates between the opposite pieces of material of said ends, one of said plates having a fastener member, the other plate having 125 a plurality of openings, either one of which being adapted to receive said fastener member, for holding the tabs permanently fastened after once being connected, lacing members connected to said plates and pass- 130

ing through certain of the eyelets which are carried by the remote portions of the plates, for drawing the tabs into overlapping positions, whereby said fastener may enter one of said openings.

5. The combination with the body of a pair of corsets, of a pair of tabs connected to the opposite sides of the corset and having their ends overlapping, stiffening members of substantial width and height embedded in said overlapping ends, one of said stiffening members having a plurality of fastener receiving openings, a fastener carried by the other stiffening member to enter any one of said openings, lace receiving eyelets carried by the remote portions of said stiffening members, laces connected to the remote portion of one of said stiffening members and passing through the eyelet carried by the remote portion of the stiffening member, a pair of lacings connected to the extremity of the tab which carries the fastener receiving openings and passing through the other eyelet, said lacings when drawn tight 25 acting to pull the tabs together in overlapping positions, whereby the fastener may enter one of said openings, to hold the tabs securely connected.

6. The combination with the body of a pair of corsets, of a pair of tabs connected to the opposite sides of the corset and having overlapping end portions, one of said end portions having a plurality of openings, the other end portion having a fastener member to enter any one of said openings, lace receiving eyelets carried by the overlapping ends and disposed remotely from the extreme edges of said ends, laces connected adjacent the extreme edge of the overlapping end and passing through the eyelet of said overlapping end, a pair of laces connected to the overlapping end of one tab remotely from its extreme edge, and passing through the lace receiving eyelet of the underlapping end, said laces of both ends

adapted, when pulled to draw the tabs in overlapping positions, whereby said fastener may enter one of said openings.

7. The combination with a pair of corsets, of a pair of tabs connected to the opposite sides of the corset, the ends of the tabs adapted to overlap, the end of one tab having a plurality of openings, the end of the other tab having a fastener to enter any one of said openings, said tabs having lace receiving openings remote from the extreme edges of said ends, pairs of laces, one pair connected to one tab remote from its extreme end edge, the other pair connected to the other tab adjacent its extreme end edge, said laces passing respectively through said lace receiving openings and adapted to be drawn toward each other, whereby the tabs may be tightened and positioning the fastener to enter one of said openings.

8. The combination with a pair of corsets, of a pair of tabs connected to the opposite sides of the corset, the ends of the tabs adapted to overlap, the end of one tab having a plurality of openings, the end of the other tab having a fastener to enter any one of said openings, said tabs having lace receiving openings remote from the extreme edges of said ends, pairs of laces, one pair connected to one tab remote from its extreme end edge, the other pair connected to the other tab adjacent its extreme end edge, said laces passing respectively through said lace receiving openings and adapted to be drawn toward each other, whereby the tabs may be tightened and positioning the fastener to enter one of said openings, and adjustable elastic connections constituting means for tightening the opposite sides of the corset, to insure holding the body firm and supporting fat and holding the body shapely.

In testimony whereof I hereunto affix my signature.

CHARLES W. LINSCOTT.
